ARRANGEMENT FOR COUNTING

PIECES OF CLOTH

William E. Blume, 126-13 101st Ave.,
Richmond Hill, N.Y. 11419
Filed Oct. 21, 1965, Ser. No. 499,695
3 Claims. (Cl. 235-98)

This invention relates to a new laundry counter, and in particular to the automatic counter arrangement for lightly soiled, medium soiled and for heavily soiled pieces of cloth adapted to count pieces of cloth of the above mentioned groups or providing total count for all or some of the above groups.

It is therefore an object of this invention to provide a counting device adapted to count pieces of cloth found in the lightly soiled, medium soiled and heavily soiled groups of laundry.

Another object of this invention is to provide a counting device adapted to combine the results of the lightly soiled, medium soiled and heavily soiled groups of laundry and to obtain the net sum of laundry found of all above-mentioned groups.

Another object of this invention is to count pieces of cloth by means of photoelectric light beams.

Another object of this invention is to provide separate endless belts for carrying separately the lightly soiled, medium soiled and heavily soiled pieces of cloth into their respective baskets.

Another object of this invention is to provide printed record for the accounted pieces of cloth in separate groups or for the total amount if pieces of cloth found in all groups.

Still another object of the invention is to produce a machine which is suitable for the indicated use and which can be simply and economically constructed.

These and other objects of this invention will be more apparent after referring to the following specification and the attached drawings in which:

FIGURE 1a is an elevated view of the laundry counter apparatus predominantly showing conveyor belt and housing;

FIGURE 1b is a continuation of the elevated view shown in FIG. 1a with parts of the structure broken away;

FIGURE 2 is a top view of the apparatus shown in FIGS. 1a, 1b with parts of the structure broken away;

FIGURE 3 shows a top view of the washing machines having the baskets positioned nearby;

FIGURE 4 is a perspective view of a preferred form of the cabinet with parts of the structure broken away;

FIGURE 5 is a side view of the cabinet shown in FIG. 4 wherein the back door of the cabinet is shown in the open position;

FIGURE 6 is a schematic diagram of light source, photocell and counter arrangements and their connections to the main counter;

FIGURE 7 is a perspective view of the main counter having a portion broken away; and

FIGURE 8 is a modified form of the invention, depicting automatically controlled removal of the full basket by releasing the cart brake.

Referring now to the drawings 1 to 7 by reference characters, there is shown a laundry counter generally indicated as 10. A receptacle 12, having an opening 14 therein, for receiving pieces of cloth is shown. A ledge 16 fastened to the inside wall of the receptacle and adapted to support the upper edge of container or bucket 18 when pieces of cloth are disposed or dumped into the receptacle. A platform 20 capable of supporting a person for disposing the pieces of cloth from upturned buckets

2

18 is mounted close to the receptacle 12 opposite an opening 22 in the receptacle. A rotatable roller 24 mounted within the bottom portion of the receptacle 12 is connected by means of an endless conveyor belt 28 to another roller 26 positioned on the same horizontal plane as the roller 24. A rotary pronged pickup device 12a is driven from roller 24 by pulley 24' to transfer clothes from opening 14 to opening 14' separated by wall 12'. The other roller 26 is rotatably mounted on the rigid stand 30 which is positioned near the outgoing end of the housing 32. Within the receptacle 12 there is a shield 34 fixedly mounted to the inside wall of the receptacle and positioned above the upper stretch of the belt 28 at the roller 24. This shield is positioned in such a manner that it prevents the pieces of cloth from slipping under the roller 24. Legs 36 are provided for the receptacle 12 so that rollers 24 and 26 could be maintained on the same horizontal plane with each other.

Next to the receptacle 12 there is motor means 38 which is adapted to turn the driving rollers 40, 42 and 44. These rollers are vertically spaced from each other and are shielded from the conveyor belt 28 by a metallic shield 46. Motor means is also connected to the belt tensioning rollers 48, 50, 52 which are vertically spaced from each other, and are adapted to provide tension to endless pick-up belts 54, 56, 58. These belts extend past housing 32 and are also engaged by rotatable rollers 60, 62, 64 which are spaced from each other in an inclined manner. Furthermore, beneath the bottom portion of each belt there are tensioning rollers 66, 68, 70 which are also spaced from each other in an inclined manner. Thus, the endless belt 54 is adapted to be moved in a clockwise direction by the driving roller 40. This belt extends horizontally past housing 32 and winds around the outside portion of rotatable roller 60, which is connected to the ceiling 72 by means of a support frame 74. The bottom portion of the endless belt 54 is engaged by rotatable tension roller 66 which is mounted in any convenient fashion to the support frame 74 and then the bottom portion of belt 54 is engaged by another tensioning roller 48 rotatably mounted on the motor means 38. The endless belt 56 is adapted to be moved in a clockwise direction by the driving roller 42, this belt extending horizontally past housing 32 and winding around the outside portion of the rotatable roller 62, which is connected to the ceiling 72 by means of support frame 76. The bottom portion of the endless belt 56 is engaged by rotatable tension roller 68, which is mounted in any convenient fashion to the support frame 76, and then the bottom portion of belt 56 is engaged by another tensioning roller 50 rotatably mounted on motor means 38. The endless belt 58 is adapted to be moved in a clockwise direction by the driving roller 44, this belt extending horizontally past conveyor housing 32 but terminating before roller 62 and tensioning roller 68. Belt 58 winds around the outside portion of the rotatable roller 64, which is connected to the ceiling 72 by means of support frame 78. The bottom portion of the endless belt 58 is engaged by rotatable tension roller 70, which is mounted in any convenient fashion to the support frame 78, and then the bottom portion of the belt 58 is engaged by another tensioning roller 52 rotatably mounted on motor means 38. It should be noted that endless belts 54, 56, 58 are spaced from each other at equal distances and positioned one above the other.

The conveyor housing 32 comprises cabinets 32a, 32b, 32c which are constructed out of sheet metal. Each of the cabinets have a front side 80a, 80b, 80c, a back side 82a, 82b, 82c and a top side 83a, 83b, 83c. Back and front sides are rigidly connected with each other by means of steel beams 84 in any desired fashion. The upper portion of the front side of cabinet 32a shows three openings 86a,

88a, 90a which are of rectangular configuration and are positioned one above the other. The upper portions of the front side of cabinet 32b and 32c have identical openings 86b, 88b, 90b and 86c, 88c, 90c. Top side 83a of cabinet 32a can be opened when stud 92 of the latch arrangement 94 is lifted thus releasing door 96 when it is necessary to perform maintenance duties or disengage conveyor housing 32 from the belts. Doors 96 are supported on hinges 95 one end of which is connected to the back sides 82a, 82b, 82c, respectively. Top side 83b and top side 83c have identical arrangements for releasing their respective doors 96 at the top side 83a of the cabinet 32a. It should be noted that the upper portions of the sides of the respective cabinets 32a, 32b, 32c are open to receive endless belts 54, 56, 58 in such a manner that the openings 86a, 86b, 86c are adapted to be used for disposal of pieces of laundry on endless pick-up belt 54. Openings 88a, 88b, 88c are adapted to be used for disposal of laundry on endless pick-up belt 56 and openings 90a, 90b, 90c are adapted to be used with endless belt 58. In order to facilitate easier moving or positioning of the cabinets, underneath each cabinet 32a, 32b, 32c a caster wheel arrangement 98 is provided (see FIG. 5).

As clearly shown in FIG. 4, in cabinet 32a, light source units 100a, 100a' and 100a'' are mounted on the inside of the frame 80a at side 104a thereof and one side of the openings 86a, 88a, 90a. On the opposite side of the openings and on the frame 80a, mirrors 100, 100' and 100'' are mounted. On the one side of the frame 80a is a photocell 102a and a control unit 108a for operating the counter 110a which is mounted on the outside of frame 80a and on the opposite side of the light source unit 100a which is adapted to transmit from mirror 100 a direct light beam to the photocell 102a. Control unit 108a is directly connected with counter 110a by means of wire 112a and counter 110a is connected with another horizontally disposed counter 110a by means of wire 114a and a connector unit 116a. The light source unit 100a' is mounted on the inside of frame 80a and positioned near one side 104a' of the opening 88a. A photocell 102a' is mounted on the inside of the frame 80a near the opening 88a to receive light from mirror 100'. On the outside of frame 80a and on the opposite side of photocell 102a' control unit 108a' is provided for operating the counter 110a' which is mounted on the outside of frame 80a and on the opposite side of the light source unit 100a' which is adapted to direct the light beam to the photocell 102a'. Control unit 108a' is directly connected with counter 110a' by means of wire 114a' and a connector unit 116a'. A light source unit 100a'' is mounted on the inside frame 80a and positioned near one side 104a'' of the opening 90a. A photocell 102a'' is mounted on the inside of the frame 80a of the opening 90a to receive light from light source 100a'' and mirror 100''. A photocell 102a'' and control unit 108a'' is provided for operating the counter 110a'' which is mounted on the outside of frame 80a and on the opposite side of the light source unit 100a'' which is adapted to direct the light beam from mirror 100'' to the photocell 102a''. Control unit 108a'' is directly connected with counter 110a'' by means of wire 112a'' and counter 110a'' is also with another horizontally disposed counter 110b''.

It should be noted that in cabinets 32b and 32c all the components are identical and correspond with the components found in cabinet 32a. Thus, in cabinet 32b the photocells are designated as 102b, 102b', 102b''; the light source units are 100b, 102b', 102b''; counters are 110b, 110b', 110b'' and the like. In cabinet 32c the photocells are 102c, 102c', 102c''; the light source units are 100c, 100c', 100c''; counters are 110c, 110c', 110c'' and the like.

It can be seen from FIG. 6 that all counters are connected to main counter 118. In the front portion 119 of the main counter is shown that the sum of numerical

values found in counters 110a, 110b, 110c comprise row A. The corresponding subsequent rows of counters comprise row B and row C respectively. Total additions for each row are shown on indicators 120a, 120b, 120c located on front portion 119 of the main counter 120. Side portion 122 of the main counter 118 features an automatic reset key 124 which is adapted to eliminate all the numerical values appearing in the indicators 120a, 120b, 120c and reset the main counter 120 for new operations. Each row is provided with a push button 126a, 126b, 126c and slots 128a, 128b, 128c. In addition to the above-mentioned slots and buttons, a slot 130 and a button 132 are provided. On the top of slot 130 an inscription is made depicting the word "TOTAL." As can be seen from the cutout in the main counter 118 in the back of each slot provisions are made for rolls of tabulating paper 134. The main counter is also connected to a power source of 120c.

In operation when, for example, button 126a is pushed a slip of tabulating paper 134 will slide out of slot 128a. On this slip of paper the total amount of laundry pieces of row A (i.e. counted by counters 110a, 110b, 110c) will be indicated. If button 132 is pushed the slip of paper will depict the total amount of laundry counted by all counters in rows A, B and C. Main counter 118 is fixedly mounted to the control panel 136 which, in turn, is mounted on a stand 138 in any acceptable manner.

Furthermore, it should be noted that pieces of cloth leaving the endless belt 58 drop to the basket 140; pieces of cloth leaving the endless belt 56 drop to the basket 142; and pieces of cloth leaving the conveyor belt 54 drop to the basket 144. Each of the baskets is connected with the wheel means 146 which are adapted to travel on rails 148. In order to make it certain that none of the laundry pieces will not fall on the floor 150, guide plate 152 is provided for the basket 144 and attached thereto in any acceptable manner. Similarly, a guide plate 154 is provided for the basket 142 and mounted thereto in any suitable manner.

As shown in FIGS. 2 and 3 full baskets 140, 142, 144 are driven on rails 148 to their respective washing machines. There the baskets 140 are unloaded into washing machine 156; baskets 142 are unloaded into washing machine 158; and the baskets 144 are unloaded into washing machine 160.

In operation, the laundry pieces reaching conveyor belt 28 are sorted out by operators, who throw or cast the heavily soiled pieces one after another through openings 86a, 86b, 86c. These pieces before landing on endless pick-up belt 54 penetrate through the light beams positioned between photo cells 102a, 102b, 102c and light sources 100a, 100b, 100c. The momentum of the passing laundry piece interrupts the light beams. The interruption of each of the light beams actuates photoelectric circuit, 55 which in turn causes the electric counters 110a, 110b, 110c to operate and to indicate the true number of times the light beams have been interrupted and thereby perform a counting function. The medium soiled pieces are thrown one after another through the openings 102a', 102b', 60 102c' and interrupt the corresponding light beams in a manner identical with the previously described procedure and registering corresponding numerical values on the electric counters. The lightly soiled pieces also pass through their respective light beams, are counted and land 65 on the endless belt 58 in a manner which is identical with the operation described in connection with the heavily and medium soiled laundry pieces. For example, due to the clockwise movement of the belt 58 the least soiled laundry pieces land in a basket A (140). When the basket 70 is filled up, the basket A is dispatched to the washing machine 156. For sake of record keeping, the button 126c is pushed to receive a paper slip 134 indicating the total number of laundry pieces in the basket A. It should be noted that previously described operations can be performed in connection with counting of medium and

heavily soiled pieces, i.e., rows B and A, respectively. If the operator desires to count all the laundry pieces found in baskets A, B and C and to have a record thereof the button 132 is pushed.

In the modified form of this invention, as shown in FIG. 8, the laundry pieces which land in the basket 210, from the moving endless belt 200 mounted on rollers 202 (one shown), are interrupting a light beam formed by a light source 204 mounted on the wall 218 and a photocell 206 mounted on the wall 220. A counter 208 connected to the photocell 206 is adapted to count interruptions of the light beam, i.e., pieces of laundry passing through the light beam and falling into the basket 210. When the basket is filled up with laundry pieces, i.e., when the predetermined number of laundry pieces is registered by counter 208, the cart brake 214 is released causing the wheel means 212, upon which the basket 210 is mounted, to drive the basket to its assigned washing machine (not shown). The rails 216 between the washing machine and the cart brake 214 are slightly inclined thus providing sufficient driving momentum for the wheels 212. It should be noted that this modified form of the invention eliminates the need to watch the main counter and then manually dispatch the basket to the washing machine. The electric power for counter 208, light source 204, photocell 206 and cart brake is provided by the power source 220.

Materials of construction are those that are conventionally used of like parts in other machines. Thus endless belts may be of canvas. The light sources, photocells and canvas are simple and effective in operation and the count is not affected by crumpled laundry pieces.

It will be understood that it is intended to cover all changes and modifications of the example of the invention herein chosen for the purpose of illustration which do not constitute departures from the spirit of the invention.

What is claimed is:

1. An arrangement for counting pieces of cloth comprising a receptacle having an opening at the top thereof for admitting said pieces of cloth into said receptacle, said receptacle having a cutout at the lower portion thereof, horizontally disposed endless conveyor means adapted to transport said pieces of cloth, one end of said conveyor means extending through said cutout into said lower portion of said receptacle, a rotatable roller secured to said lower portion of said receptacle, a stand spaced from said receptacle, another roller rotatably mounted on said stand, said endless conveyor means operatively engaging both of said rollers, a housing including a plurality of cabinets, each of said cabinets having a front portion, a back portion, a top portion, said side portions and said bottom portion, said front portion of said cabinet having a number of vertically positioned rectangular openings, endless belt means including horizontally positioned pick-up belts positioned one above the other within said housing, said pick-up belts positioned in such a manner that they are adapted to receive said pieces of cloth through said openings, each of said side portions of said housing having openings therein, said pick-up belts adapted to extend outside of said housing through said openings in said end portions of said housing, said driving means adapted to drive said pick-up belts, counting means fixedly mounted at each of said openings of said housing and being adapted to count said pieces of cloth during their transfer from said conveyor means to said belt means, said counting means including a light source unit, a photocell horizontally spaced from said light source unit, both said light source unit and said photocell being fixedly mounted on the inside of said front portion of each of said cabinets and near each end of one of said openings, said light source unit causing a horizontal light beam to be dispatched into said photocell, a control unit being positioned on the outside of said front portion and on the opposite side of said photocell, a counter attached on the

outside of said front portion and on the opposite side of said light source unit, said control unit adapted to control the operation of said counter in accordance with the interruptions of said light beam in such a manner that each interruption of light beam causes a numerical addition within said counter, counter means positioned at each of said openings within each of said cabinets, said counters connected to each other in such a manner that they form horizontal rows of counters, main counting means connected to each of said horizontal rows of counters, said counting means being adapted to add numerical values obtained from each counter thus obtaining numerical values for each of the horizontal rows and said main counting means capable of adding said numerical values obtained from each of said horizontal rows of counters, said main counting means including an adding and recording apparatus having a front panel, side panels, a back panel, a top panel and a bottom panel, said front panel of said apparatus including a plurality of numerical indicators vertically spaced from each other, each of said indicators being adapted to show the total addition of the numerical values registered by all of said counters of each of said horizontal rows, a control panel to which said adding and recording apparatus is fixedly attached, and power supply means for supporting electric power to said counting means and said counters.

2. An arrangement as in claim 1, wherein one of said side panels has a plurality of slots vertically spaced from each other, said side panels having a plurality of holes vertically spaced from each other and from said slots, each of said holes being in horizontal alignment with each of said slots and with one of said numerical indicators of said front panel, a plurality of rolls of strip paper positioned inside of said apparatus in such a manner that said strip of paper of each roll is arranged to be slid out from each of said slots, printing means within said apparatus adapted to print the information appearing in one of said numerical indicators, push buttons positioned within said holes, when one of said pushbuttons is depressed, said printing means adapted to print said numerical value appearing in corresponding numerical indicator on said front panel, said strip of paper with said numerical value printed thereon and extending outside of said apparatus through one of said slots thus providing printed record of said total numerical value appearing in one of said horizontal rows of counters in accordance with the visual indication of said corresponding numerical indicator of said front panel of said apparatus, the bottom pushbutton and the bottom slot of said side panel of said apparatus, addition means within said apparatus adapted to add the numerical values of each of said numerical indicators, upon depression of said last pushbutton, said strip of paper caused to slide out of said bottom slot and thus providing printed record of said total numerical value appearing in all numerical indicators at any given time, and automatic reset for eliminating said numerical values from said counters and said numerical indicators.

3. An arrangement for counting pieces of cloth comprising, a receptacle having an opening at the top thereof for admitting said pieces of cloth into said receptacle, said receptacle having a cutout at the lower portion thereof, horizontally disposed endless conveyor means adapted to transport said pieces of cloth, one end of said conveyor means extending through said cutout into said lower portion of said receptacle, a rotatable roller secured to said lower portion of said receptacle, a stand spaced from said receptacle, another roller rotatably mounted on said stand, said endless conveyor means operatively engaging both of said rollers, a housing including a plurality of cabinets, each of said cabinets having a front portion, a back portion, a top portion, said side portions and said bottom portion, said front portion of said cabinet having a number of vertically positioned rectangular openings, endless belt means including horizontally positioned pick-up belts positioned one above the other within said housing, said pick-up belts positioned in such a manner that they are adapted to receive said pieces of cloth through said openings, each of said side portions of said housing having openings therein, said pick-up belts adapted to extend outside of said housing through said openings in said end portions of said housing, said driving means adapted to drive said pick-up belts, counting means fixedly mounted at each of said openings of said housing and being adapted to count said pieces of cloth during their transfer from said conveyor means to said belt means, said counting means including a light source unit, a photocell horizontally spaced from said light source unit, both said light source unit and said photocell being fixedly mounted on the inside of said front portion of each of said cabinets and near each end of one of said openings, said light source unit causing a horizontal light beam to be dispatched into said photocell, a control unit being positioned on the outside of said front portion and on the opposite side of said photocell, a counter attached on the

tally positioned pick-up belts positioned one above the other within said housing, said pick-up belts positioned in such a manner that they are adapted to receive said pieces of cloth through said openings, each of said side portions of said housing having openings therein, said pick-up belts adapted to extend outside of said housing through said openings in said end portions of said housing, said driving means including a first group of rollers and tensioning rollers and a second group of rollers and tensioning rollers, both groups being horizontally disposed from each other, endless pick-up belt adapted to operatively engage one roller from said second group, counting means including a light source unit, a photocell and an electric counter, said light source unit adapted to project a light beam on said photocell, said counting means attached at 15 said openings of said cabinets whereby numerical values are registered by said counters when said light source is interrupted, horizontal rows of counting means for addition of numerical values, main counting means connected to each row of counting means, adapted to add and print all interruptions of said light beam within said rows of 20 said counting means, indicating means on main counting means depicting interruptions of said light beam within each of said rows, and power supply means for providing

electric power for said main counting means and said counting means.
